(57) **CLAIM**

What is claimed is the ornamental design for a novelty key chain, as shown and described.

DESCRIPTION

FIG. 1 is an isometric view of the novelty key chain;
FIG. 2 is a front view of the novelty key chain;
FIG. 3 is a back view of the novelty key chain;
FIG. 4 is a right-side view of the novelty key chain;
FIG. 5 is a left-side view of the novelty key chain;
FIG. 6 is a top view of the novelty key chain; and,
FIG. 7 is a bottom view of the novelty key chain.
Elements illustrated with broken lines are for illustration
only and form no part of the design claimed.
